(57) **CLAIM**

The ornamental design for a double ended drawing tool, as shown and described.

DESCRIPTION

FIG. 1 is a top perspective view of my new design for a double ended drawing tool.

FIG. 2 is a top plan view of my new design for a double ended drawing tool.

FIG. 3 is a bottom plan view of my new design for a double ended drawing tool.

FIG. 4 is a right side elevation view of my new design for a double ended drawing tool.

FIG. 5 is a left side elevation view of my new design for a double ended drawing tool.

FIG. 6 is a front elevation view of my new design for a double ended drawing tool; and,

FIG. 7 is a rear elevation view of my new design for a double ended drawing tool.
